UNITED STATES PATENT OFFICE.

FERDINAND C. REINHARD, OF WEST PITTSBURG, PENNSYLVANIA.

CLOTHESLINE-FASTENER.

1,368,754.

Specification of Letters Patent. Patented Feb. 15, 1921.

Application filed December 5, 1919. Serial No. 342,622.

To all whom it may concern:

Be it known that I, FERDINAND C. REINHARD, a resident of West Pittsburg, in the county of Lawrence and State of Pennsylvania, have invented a new and useful Improvement in Clothesline-Fasteners, of which the following is a specification.

This invention relates to clothes line fasteners, and the object thereof is to provide a 10 fastener of simple and inexpensive construction whereby a clothes line may be easily drawn taut between two supports and quickly fastened while held taut.

In the accompanying sheet of drawings, 15 which forms part of this specification, the preferred embodiment of the invention is illustrated. Figure 1 is a perspective view of the fastener shown attached to a support, the view also shows the manner in 20 which a clothes line may be held by the fastener; and Fig. 2 is a perspective view of the fastener detached from its support.

The fastener includes three portions, 25 namely, an outwardly and upwardly extending hook at its top around which a clothes line may be drawn taut, outwardly extending parallel spring arms at its bottom, between which arms a clothes line may be clamped after having been drawn taut 30 around the hook, and an intermediate portion connected to the hook and the spring arms or clamp and adapted to be firmly attached to a support.

While the fastener may be formed of any 35 suitable material, it is preferably made of a single strip of metal such as heavy gage wire. When so constructed, the hook is preferably formed by doubling the central portion of the wire upon itself and shaping 40 it to have an outwardly extending portion 1 and an upwardly extending portion 2. The body or intermediate portion 3 of the fastener may be formed by bending the parallel portions of the wire substantially at 45 right angles to the hook portion 1; and, to prevent the fastener from turning sidewise when attached to a support, the lower ends of the intermediate portion may be flared outwardly as indicated at 4; the outwardly 50 flared portions being adapted to bear against the support to which the fastener is attached.

The spring arms or clamp are formed by bending the wire outwardly from the portion 4 to form adjacently disposed parallel arms 5, held yieldingly toward each other by

the resiliency of the material of which the fastener is made. The outer ends of the arms 5 are preferably bent laterally and turned rearwardly to form line engaging 60 hooks 6 adapted to prevent the line from slipping from the end of the spring arms. As will be seen the ends of the hooks 6 are preferably spaced from the arms 5 so that a line may be inserted between each end and 65 its adjacent arm.

In use the fastener may be attached to a post or other support 7 by means of a suitable clamp 8 which engages the intermediate portion 3 of the fastener, and which 70 may be secured to the post 7 by fastening members, such as screws 9. To attach a clothes line 10 to the fastener, the line is first placed around the hook 1, 2 and may then be drawn taut by pulling upon the line. When 75 the line is thus stretched, and while so held by the person putting the line up, it is pressed between the outer ends of the spring arms 5, which are effective to temporarily hold the line. While thus held, the line may 80 be wrapped around and between the arms 5 in the form of a figure 8, as indicated in the drawing. The free end of the line may then be looped around the hook 1, 2, and from such hook it will extend to the next 85 support. By looping the line around and between the arms 5 in the manner just explained, either of the line sections leading from the hook 1, 2 may break and the other line section will not fall or become loosened. 90 That such is the case may be readily understood by observing that the greater the tension placed upon one line section, the tighter the line will be bound between the arms 5.

In case it is desired to attach the end of 95 a line to the fastener, such end may be knotted and the line placed between one of the hooks 6 and the adjacent arm 5, the knot being of such size that it may not be drawn between the hook and arm. The line may 100 then be wrapped around and between the arms as indicated in Fig. 1 and be looped over the hook 1, 2. It will of course be understood that the line may be engaged and fastened by the fastener otherwise than as 105 has been particularly explained.

It will be observed of the clothes fastener that it may be very easily and inexpensively manufactured, and that it may be readily attached to the usual form of clothes line 110 post. When thus attached in its intended position, the fastener affords convenient

means of stretching a clothes line and for securely fastening it after it has been stretched.

According to the provisions of the patent 5 statute, I have described the principle and manner of use of my invention together with the construction which I now consider to represent the best embodiment thereof. However, I desire to have it understood that, 10 within the scope of the appended claims, my invention may be practised by other forms of construction than that specifically shown and described herewith.

I claim:

- 15 1. A clothes line fastener adapted to be rigidly attached to a support and when so attached comprising a line stretching hook at its upper end, a pair of outwardly extending spring arms at its bottom forming a line clamp, said arms having free ends extending laterally outwardly, and an intermediate portion connecting said hook and clamp and adapted to be secured in vertical position to a support.
- 20 25 2. A clothes line fastener adapted to be rigidly attached to a support and when so attached comprising an outwardly and upwardly extending portion at the top forming a line stretching hook, an outwardly

extending pair of spring arms at the bottom forming a line clamp, the outer ends of said arms being free and being turned rearwardly adjacent to but spaced from the outer sides of said arms, and an intermediate portion connecting said hook and clamp 35 and adapted to be secured to a support.

3. A clothes line fastener adapted to be rigidly attached to a support and when so attached comprising an outwardly and upwardly extending portion at the top forming 40 a line stretching hook, an outwardly extending pair of spring arms at the bottom forming a line clamp, the outer ends of said arms being free and being turned rearwardly adjacent to but spaced from the outer sides 45 of said arms, and an intermediate portion connecting said hook and clamp and adapted to be secured to a support, said fastener being formed of a single strip of metal of which the central portion is the upper end 50 of said hook and of which the ends are said ends of the spring arms.

In testimony whereof, I have hereunto set my hand.

FERDINAND C. REINHARD.
